UNITED STATES PATENT OFFICE

ALFRED HARRINGTON, OF LEICESTER, ENGLAND, ASSIGNOR TO UNITED SHOE MACHINERY CORPORATION, OF PATERSON, NEW JERSEY, A CORPORATION OF NEW JERSEY

SOLE EDGE WAXING MACHINE

Application filed October 29, 1930, Serial No. 491,976, and in Great Britain November 13, 1929.

This invention relates to sole edge coating machines and is herein illustrated as embodied in a machine particularly designed for applying wax to the edges of the soles of boots and shoes prior to burnishing operations.

In order to improve the effect of the burnishing operation upon the edge of the sole of a shoe, which operation is commonly called edge setting, it frequently is found desirable to apply wax to the edge of the sole prior to the burnishing operation so that a higher polish will be obtained and one which will be more permanent. In some instances the wax is applied from a stick which is rubbed over the edge of the sole, and in other cases the wax is liquefied and applied with a brush or sponge. Sometimes also the wax is combined with a stain. Such methods of wax applying are liable to be wasteful of wax and irregular in results mainly because of the difficulty in transferring the desired small quantity of wax to each part of the sole edge in a properly molten condition. It is common knowledge, moreover, that the waxes most suitable for this purpose, carnauba wax being an example of such a wax, are those which are relatively hard and brittle at ordinary temperatures but which can be readily applied when they are liquefied by the application of heat. It is difficult to transfer to a sole edge wax from a stick end, brush or sponge without cooling off the wax to such an extent that it readily chips off the sole edge when a burnishing or other tool first comes into contact with it and such difficulty increases with increasing hardness of the wax.

Accordingly, one important object of the invention is to provide an improved machine by means of which the edges of the soles of boots and shoes may be coated evenly and thoroughly and the operation performed even more rapidly than by hand and without requiring the use of skilled labor.

In the illustrated machine wax is applied to the work by means of a driven roll which preferably is constructed of absorbent material such as felt and the wax is delivered to this felt roll from a supplying roll which

receives it drop by drop from an overhead reservoir. Since shoes are only intermittently presented to the applying roll, it is impossible exactly to coordinate the supply of wax with the amount which is used up on the shoes. It has been found, however, that an even application of wax to the pieces of work may be assured by means of a novel arrangement of the above-mentioned parts. Thus, in accordance with an important feature of the invention, the supplying roll is independently driven to rotate toward the upper part of the applying roll and the wax is deposited upon the upper surface of the supplying roll and carried thereby to the other roll. Preferably, and as herein illustrated, the applying roll rotates in the opposite direction from that of the supplying roll so that its upper part also approaches the latter roll. This results in storing up a small quantity of wax between the rolls immediately above and below the line of closest approach of the rolls, thereby producing a useful reserve of wax supply and rendering it unnecessary to set the flow of wax from the reservoir to the supplying wheel with great exactitude.

Such a felt roll, while applying a uniform coating when new, is easily deformed by the pressure of the work and may become so misshapen that it no longer applies the wax evenly. In accordance with another feature of the invention, and as illustrated, the supplying roll has an end flange which overlaps the end of the applying roll so that in addition to the contact of the periphery of the roll there is an engagement of the flange with the end of the felt roll and a sharp corner is maintained upon the felt roll as well as an even periphery. As illustrated, also, the felt roll is mounted on a projection of its drive shaft and is held against axial removal by the flange of the supplying roll.

Still another feature of the invention resides in a novel arrangement for applying heat to a combustible roll such as the felt applying roll mentioned above. As illustrated, the roll carrier has an outstanding flange supporting the roll and heat is supplied to the felt roll through this flange.

This arrangement preferably also includes means for minimizing the transfer of heat to the shaft driving the applying roll so that the lubrication thereof will not be affected.

5 In accordance with still other features of the invention, the applying roll of the illustrated machine is supported in a bracket mounted upon an upright pivot and arranged so that the pressure between the applying 10 roll and the supplying roll may be adjusted to give a degree of control of the quantity of wax which the felt roll will give up. Carried upon the illustrated bracket for adjustment with the applying roll and in adjustable 15 relation thereto, are a plurality of gages arranged for use alternatively in accordance with the style of work to be treated. One of these gages, for example, is intended for engagement with the bottoms of the soles of 20 men's shoes where the edges are substantially normal to the bottoms. When it is desired to use the machine for women's shoes, the other gage, which is a crease gage in the form of a rotatable disk, is preferably utilized, this 25 gage projecting slightly beyond the periphery of the felt roll to engage the crease between the upper edge of the sole and the shoe upper. This gage is supported upon the carrier for the applying roll both for adjustment of position with respect to the periphery 30 of that roll and also for bodily displacement with respect thereto.

These and other features of the invention are more fully described herein, reference being had to the accompanying drawings, in 35 which

Fig. 1 is an end elevation of the machine;
Fig. 2 is a plan view thereof;

Fig. 3 is a detail view of the applying roll 40 showing the crease guiding disk in use;

Fig. 4 is an end view on an enlarged scale of said crease disk and the support therefor; and

Fig. 5 is a front elevation of the shoe bottom engaging gage showing its relation to the work and to the applying roll.

The application of wax is effected by means of a cylindrical applying roll 10, preferably constructed of felt, and coacting with this is a supplying roll 12 having an end flange 14 which overlaps the edge of the applying roll for purposes to be more fully described. As will appear from Fig. 1, these rolls are rotated in opposite directions such that the upper portions of the rolls approach each other and to this end the applying roll is carried by a shaft 16 (Fig. 2) having a drive pulley 18, while the supplying roll 12 is mounted upon a shaft 20 having a drive 55 pulley 22. Power is supplied to these pulleys from any suitable source to effect their rotation at such speeds that the peripheral speeds of the two rolls are substantially equal. The shaft 20 is journaled in bearings 60 mounted on a base 26 while the shaft 16 is 65

journaled in bearings 28 and 30 which are formed upon a carrier 32 mounted to swing about an upright pivot 34 which is clamped in a depending arm 36 forming a part of the base 26. A spring-pressed plunger 38 bears 70 against the carrier 32 to swing it in one direction so as to move the applying roll 10 away from the roll 12 and an adjusting screw 40 is provided for moving the carrier against the tension of this plunger 38 thereby to adjust the pressure between the peripheries of the two rolls and to determine the amount of wax delivered to the felt roll 10. When the screw 40 is turned far enough to bring the felt roll 10 out beyond the flange 14 of the 80 supplying roll 12, the felt roll 10 may be easily removed from its shaft 16.

The supplying roll 12 is a metallic roll, preferably hollow as indicated in Fig. 1, and heated by a flame from a gas jet supplied by the pipe 42. The heating of the felt roll 10, because of its combustible nature, is not so easy, however, and for this reason the roll 10 is supported as shown in Fig. 3. It will be seen that a carrying member 44 constituting an extension of the shaft 16 is provided to support the felt roll 10 and this carrying member 44 has a flange 46 at the back of the roll and a central projection 48 of reduced diameter upon which the felt roll is mounted by endwise positioning movement. In order to make sure that the felt roll will be rotated with the carrying member 44, the flange 46 is also provided with a pin 50 which enters the felt roll when the latter is mounted on the shaft. It is possible, with this arrangement, to supply heat to the felt roll by a gas flame 52, to which gas is supplied through a pipe 54, directed against the rear face of the flange 46, thus permitting the 95 heat to be transferred to the felt roll without setting it afire. In order that the heat supplied to the carrying member 44 may not be transferred back to the shaft 16 and thereby interfere with the lubrication of the bearings 28 and 30, said extension is secured to the shaft 16 by an insulated mounting comprising a projecting end portion 56 on the extension which is received within a recess formed in an enlarged portion 58 of the shaft 115 16 and is held therein by screws 60 spaced around the enlarged portion 58 and furnishing means for centering the extension upon the shaft 16. At the same time the screws furnish a minimum path for the transfer of 120 heat back to the shaft 16, and the air between the projection 56 and the recessed portion 58 helps to insulate the tool.

It may be desired to supply waxes of different colors to different batches of work 125 and to this end a plurality of wax pots 62 and 64 are adapted to be alternately positioned above the supplying roll 12. The interchange of these pots is facilitated by mounting them upon an upright pivot 66 in 130

the base 26. Each of the wax pots, as best shown in Fig. 1, has heating means such as an electric unit 68 whereby the wax is kept in fluid condition and from these pots the wax is delivered drop by drop through an outlet nozzle 70 which is controlled by an adjusting screw 72. In order that pieces of work such as the soles of substantially completed shoes may be presented to the wax applying roll 10 and turned to present all portions of the sole edges thereto, the machine is provided with alternative gages comprising a shoe bottom gage 74 and a crease guide disk 76 which are mounted on the carrier 32 for adjustment with the roll 10 when the screw 40 is turned. These are not intended to be used together, but one or the other is selected in accordance with the character of the work to be treated, it being understood that the shoes are held with the soles substantially in an upright plane, as indicated by the dotted outline 78 in Fig. 1, and turned to present all parts of the sole edges. If the work comprises men's shoes, such as shown in Fig. 5, having a broad edged sole 80 to be treated by the applying roll 10, then the shoe bottom gage 74 is swung from the position shown in Figs. 1 and 2 to a horizontal position indicated in Fig. 5 in which the rounded button forming the gage 74 is in position for engagement with the bottom of the sole 80. Provision is made for adjusting the position of this gage to accommodate variations in the thickness of the sole, as, for example, between the forepart and the shank, or to allow the heels of the shoes to be waxed at the same time, as may be desired in Veldtschoen or stitchdown work. Accordingly the gage 74 is mounted on a rod 82 slidable in a bracket 84 which is mounted on a pivot pin 86 in the carrier 32. This bracket 84 may therefore be turned from a horizontal position, indicated in Fig. 5, to an inoperative vertical position indicated in Figs. 1 and 2. In order that it may be held in horizontal position, a spring 88 surrounding the pivot 86 bears against a collar on said pivot and a portion of the bracket 84 to press the bracket inwardly toward the carrier 32, and the carrier frame 32 has lugs 90 and 92, shown in Fig. 1, between which a projection 89 on the bracket 84 may be positioned to hold said bracket horizontal. A spring 94 surrounding the rod 82 presses against a collar 96 and thereby tends to move the button 74 toward the outer end of the felt roll 10. In opposition to the pressure of this spring is the pressure of a bell crank 98 pivoted upon the bracket and pulled down by a treadle rod 100 to move the gage 74 to the right. When pressure is released the lower arm of the bell crank 98 will engage a lug 102 on the bracket 84 thereby to limit the movement of the rod 82.

When, on the other hand, it is desired to

treat women's shoes having a relatively narrow edge, guidance of the work with respect to the felt roll to prevent the uppers of the shoes from being daubed with wax is effected by means of the crease disk 76 which projects slightly beyond the roll 10 to enter the crease between the sole 110 and the upper 112 of a woman's shoe, a portion of which is shown in section in Fig. 3. Because of variation in different styles of work it may be desired to have this disk project a greater or less distance beyond the periphery of the roll 10. Accordingly the disk is supported upon an arm 120 slotted at its upper end, as indicated in Fig. 1, and mounted by a tongue-and-groove connection on a sleeve 122 (Fig. 2) to which it is clamped by means of a screw 124. This sleeve is journaled on a pin 126 which is clamped by a set screw 127 in the upper end of an arm 128 formed as an integral extension of the carrier frame 32. Adjustment of the angular relation of the arm 120 with respect to the machine and hence of the relation between the disk and roll may be effected by means of a screw 130 threaded in the upper end of the arm 128 and having a reduced end for engagement with the side of a notch 132 cut in the rod 126. This notch 132 is large enough to allow the arm 120 to be swung to an upper position, indicated by dot and dash lines in Fig. 4, so as to permit removal of the felt roll 10 endwise of the shaft 16. A spring 134 surrounding the sleeve 122 and secured thereto and to the pin 126 urges the arm 120 on said sleeve downwardly until the screw 130 comes into engagement with the upright side of the notch 132. When this gage is not to be used it may be swung to an inoperative position or removed from the machine.

The guide disk 76 is preferably mounted as shown in Fig. 2 so as to lie at a slight angle to the outer face of the felt wheel 10 with that portion of it which projects radially beyond the periphery of the felt wheel nearest thereto, there being less likelihood of undesired transfer of wax from the felt to the guide disk by such mounting.

A change of the color of wax desired necessitates a change of the felt roll 10. Such change is facilitated by the above described mounting of the shaft 16 since it is only necessary to turn the screw 40 outwardly far enough for the felt roll 10 to be brought clear of the flange 14 so that it may be withdrawn from the end of its carrying member 44 upon which it is held as above described merely by being threaded over a central pin 48 and a smaller pin 50 which is eccentric to the axis of the member 44 and serves to rotate the roll 10. When in operation, the outer edge of the felt roll 10 is overlapped by the flange 14 on the metallic roll 12 and there is no necessity for provision of further

means for holding the felt roll 10 longitudinally of the member 44.

In effecting a change of felt roll from one color of wax to another or otherwise as required, the machine operator will turn the screw 40 so that the plunger 38 moves the shaft 16 so as to withdraw the felt roll 10 from overlapping relation with the flange 14, he will then remove the felt roll and change it for another, clean off any wax there may be on the metallic roll 12 and move the desired wax reservoir 62 or 64 into position, and will finally by turning the screw 40 cause the renewed felt roll to make contact with the roll 12.

In the actual operation of applying wax to sole edges an operator takes each shoe and manoeuvres it with its sole edge against the felt roll which is maintained saturated with molten wax. The outline of a shoe with a portion of its forepart sole edge in contact with the felt roll is shown at 78 in Fig. 1. By traversing the sole past the felt roll a film of wax is applied all around the sole edge by a constantly changed and constantly recharged applying surface, giving as a result a thin film of wax well impregnated into the sole edge surface.

When the metallic and felt rolls 12 and 10 are heated and rotated as above described and wax is fed to the former, it is rapidly transferred to the felt roll 10 and there is a tendency for waves of molten wax to be maintained on the rolls immediately above and below the line where the rolls are closest in contact. The size of these waves depends upon the excess of wax fed to the metallic roll 12 over that removed from the felt roll 10 by the work. The formation, however, of these waves produces a useful reserve wax supply since a considerable quantity of wax may be retained in such wave formation and used up by continued application of fresh work to the felt roll. Under such conditions it is not necessary to set the flow of wax from the reservoir on to the metallic roll with great exactitude, and the delivery of wax to the metallic roll may be, if desired, effected manually from time to time as necessary by manipulation of the nozzle screw 72.

Variation of the pressure with which the felt roll 10 is pressed (by reason of adjustment of its shaft) against the metallic roll 12 causes corresponding variation in the quantity of wax which the felt will readily give up when work is held against it. If a free wax delivery is desired the pressure between the two rolls is reduced, as above indicated, by adjustment of the screw 40.

If men's work, or work of a similar style in which the sole edges are flat and substantially at right angles to the sole surfaces, is to be presented to the machine, then the bottom gage 74 will be raised to its operative position and held there by engagement of the

projection 89 on the bracket 84 with the lugs 90 and 92. Work will be guided as indicated in Fig. 5 and all parts of each sole edge presented to the wax applying roll 10 by manipulation of the shoe, keeping the sole in substantially an upright plane. In the case of certain classes of work, such as stitchdowns fitted with low heels, it may be desired to wax the heel edge surface as well as the sole edge. In such a case the gage spindle 82 may be moved laterally by means of pressure applied to the treadle rod 100 so as to expose a greater width of the surface of the felt roll.

If, on the other hand, women's work is to be treated, the gage shown in Fig. 5 will be dropped to a vertical inoperative position, as indicated in Figs. 1 and 2, and the work will be guided in engagement with the crease disk 76, as indicated in Fig. 3.

Having thus described my invention, what I claim as new and desire to secure by Letters Patent of the United States is:

1. In a sole edge coating machine, an applying member of absorbent material, a rotary member for supplying coating material to said applying member, said members being driven in opposite directions upon axes substantially horizontally side by side with adjacent peripheries moving downwardly, means for depositing coating material drop by drop upon an upper portion of said supplying member, and means for controlling the rate of flow of the coating material to secure a surplus at the meeting point of the members.

2. In a sole edge waxing machine, an absorbent applying roll arranged for contact with the edge of the sole of a shoe, means for supplying wax to said applying roll comprising a rigid supplying roll independently driven toward the top of said applying roll, means for supplying wax to an upper portion of said supplying roll, said supplying roll also having a flange for engagement with the end of the applying roll, and means for adjusting the distance between the axes of said rolls thereby to adjust the quantity of wax transferred.

3. In a sole edge coating machine, a driven shaft having a carrier, an applying roll positioned upon said carrier by axial movement with respect to the carrier, and a supplying roll coacting with the periphery of said applying roll and also provided with a flange overhanging the end of the applying roll preventing displacement of said roll axially of its carrier.

4. In a sole edge coating machine, a frame, a roll journaled in said frame, a bracket mounted on an upright pivot in front of said roll, an applying member journaled in said bracket co-operating with the said first-mentioned roll, means for supplying coating material to said first-mentioned roll for delivery to said applying roll, and means for

adjusting said bracket thereby to vary the relation of the adjacent peripheries of said rolls to control the quantity of coating material delivered to the applying roll.

5 5. In a sole edge coating machine, a frame, a supplying roll journaled in said frame, an applying roll coating with said supplying roll, an adjustably mounted carrier for said applying roll whereby said applying roll may be adjusted toward and away from said supplying roll, and a gage adjustably mounted on said bracket for movement with respect to said applying roll.

10 6. In a sole edge coating machine, a frame, a supplying roll journaled in said frame, an applying roll coating with said supplying roll, an adjustably mounted carrier for said applying roll whereby said applying roll may be adjusted toward and away from said supplying roll, and alternative gages displaceably mounted upon said bracket and arranged for engagement with different portions of a shoe presented to said applying roll.

15 7. In a sole edge coating machine, a driven shaft having an outstanding flange in a plane substantially normal to the shaft, an applying roll of combustible felt readily removably mounted on said shaft in engagement with one face of the flange, a projection on the same face of said flange embedded in said felt to drive the applying roll with the shaft, and means for applying a flame to the opposite face of said flange to heat the felt.

20 8. In a sole edge coating machine, a driven carrier having an outstanding flange, a projection on said flange, an applying roll of combustible material mounted on said shaft in engagement with said flange and said projection so as to be driven thereby, means for applying heat to said flange, means for driving said shaft, and heat-insulating means interposed between said driving means and said flange.

25 9. In a sole edge coating machine, an applying member mounted upon a driven shaft,

means for adjustably supporting said shaft, and alternative gaging means associated with said applying member and arranged for engagement with different portions of a shoe, said alternative gaging means being mounted for adjustment with said applying member and also being mounted for displacement with respect to said applying member whereby either one of the gaging means may be readily brought into operative position with respect to the applying member.

30 10. In a sole edge coating machine, an applying roll, a guide disk positioned at the end of the roll to project beyond the periphery thereof, and means for supporting said disk comprising a notched stud, a bracket pivoted on said stud, means urging said bracket to swing in one direction, and a screw for adjusting the position of said bracket engaging a face of said notch in opposition to said urging means, said notch being constructed and arranged to permit movement of the screw and hence rotation of the bracket to a point where the disk is out of alignment with the end of the roll.

35 11. In a sole treating machine, a treating member, a pivoted bracket, an associated round ended gaging member slidably mounted in said bracket and adapted for engagement with the bottom of a shoe, and operator-controlled means for sliding said gaging member in said bracket to vary the relation of the gaging member to said treating member.

40 12. In a sole treating machine, a treating member, a gaging member movable with respect to said treating member, displaceable means for movably supporting said gaging means, and an operator-controlled lever pivotally mounted upon said displaceable means for variably determining the position of said gaging means.

In testimony whereof I have signed my name to this specification.

ALFRED HARRINGTON.
